(57) **CLAIM**

The ornamental design for a cordless telephone base, as shown and described.

DESCRIPTION

FIG. 1 is a front perspective view of a cordless telephone base in accordance with the present invention;

FIG. 2 is a front view of the cordless telephone base of FIG. 1;

FIG. 3 is a back view of the cordless telephone base of FIG. 1;

FIG. 4 is a left side view of the cordless telephone base of FIG. 1;

FIG. 5 is a right side view of the cordless telephone base of FIG. 1;

FIG. 6 is a top view of the cordless telephone base of FIG. 1; and,

FIG. 7 is a bottom view of the cordless telephone base of FIG. 1.

The portions drawn in broken lines are shown for illustrative purposes only and do not form part of the claimed design.
